US0D1083613S

(12) **United States Design Patent** (10) Patent No.: **US D1,083,613 S**
(45) Date of Patent: ** Jul. 15, 2025

(54) **JAR**

(71) Applicant: **TURKIYE SISE VE CAM FABRIKALARI ANONIM SIRKETI, Istanbul (TR)**

(72) Inventors: **Bahadir Haktanir, Istanbul (TR); Seher Naz Ayhan Arda, Istanbul (TR)**

(**) Term: **15 Years**

(21) Appl. No.: **35/522,678**

(22) Filed: **Aug. 6, 2024**

(80) **Hague Agreement Data**

Int. Filing Date: **Aug. 6, 2024**

Int. Reg. No.: **DM/240972**

Int. Reg. Date: **Aug. 6, 2024**

Int. Reg. Pub. Date: **Oct. 18, 2024**

(30) **Foreign Application Priority Data**

Feb. 7, 2024 (TR) 2024/001406

(51) LOC (15) Cl. **09-01**

(52) U.S. Cl.

USPC **D9/553**
